UNITED STATES PATENT OFFICE

WALTER ZWICK, OF BERLIN-WESTEND, GERMANY

PISTON MOTOR

Application filed February 9, 1931, Serial No. 514,591, and in Germany February 10, 1930.

This invention relates to a piston motor, preferably an internal combustion motor. All motors or engines of this type operate in this way that the number of the strokes of the piston or pistons is in a uniform relation to the number of the revolutions of the motor or engine shaft so that a change of the turning moment transmitted from said shaft to the machine driven by the motor with uniform performance can be brought about only by means of an intermittent gearing.

The object of the present invention is to render the use of such a gearing superfluous. To attain this object the motor is so designed that with uniform performance the turning can be changed corresponding to the requirement, preferably automatically. The invention is carried out in this way that the number of strokes of the piston or pistons is made independent of the number of revolutions of the motor shaft, preferably in this manner that the pistons are being coupled with this shaft only during a certain time, whereas during that time in which the pistons are not coupled with the motor shaft the work done by them is accumulated and is afterwards, when these members have again been coupled, transmitted to the said shaft in order to be utilized. The shorter the time in which the pistons and the shaft are coupled with one another, the shorter is, however, also the path during which energy is transmitted to the motor shaft; in other words: the number of revolutions of the motor shaft is reduced for a certain short time with the aid of a coupling provided for the piston or pistons, the turning moment being at the same time correspondingly increased. The adjustment is effected by hand or automatically by a governor of any suitable design, for instance by a torsion dynamometer, a centrifugal governor or the like.

The invention is illustrated diagrammatically and by way of example on the accompanying drawings on which Figure 1 is a section through a motor designed according to this invention, the section lying transversely to the motor shaft; Figure 2 is a similar view relating to a modification; Figure 3 is a vertical section in the plane 3—3

of Fig. 2; Figures 4 and 5 show details relating to Fig. 3 and being drawn to an enlarged scale; Figure 6 is a performance diagram disclosing the manner of operation of the motor; and Figure 7 is a section through still another constructional form of the motor, all as fully described hereinafter.

Referring to Fig. 1, 2 denotes the cylinder of the motor which is circular and stationary; within this cylinder circulate two pairs of pistons 3, 3a and 4, 4a, and the two pistons forming a pair are connected with one another by a traverse 5, or 6 respectively, and these two traverses are connected by spokes 7 with a ring 8 located loosely upon the motor shaft 9.

The motor operates as a two-cycle motor. The charge, i. e. the mixture of gas and air, is pressed into it by a blower 10; it enters first into a channel 11 and passes from this channel through apertures 12 into the cylinder. The apertures 13 are the exhaust apertures. One of the spokes is provided with a pivot 14 supporting a bell-crank lever 16, one arm of which contacts with a friction roller 15, whereas the other arm carries a roll 17 contacting with a cam disk 18 supported loosely upon the shaft 9. The roll 15 is located between the lever 16 and a friction roll 19 affixed to the shaft 9. The cam disk 18 is engaged by a guide rod 20, the other end of which is jointed to a double lever 21 which is supported on a pivot 22 secured to a bracket 23; the other arm of this lever engages the sliding member 24 of a centrifugal governor 25. The axle 26 of this governor is provided with a bevel-wheel 28, and also a pulley 29 is affixed to said axle. The pulley 29 is driven by means of a pulley 31 and a belt 30; the pulley 31 is affixed to the shaft 9.

The cylinder 2 is divided by partition walls 32 and 33 into two chambers of semi-circular shape, and in each thereof one of the two pairs of pistons is housed.

The operation of this motor is as follows:

When the parts are in the position shown in Fig. 1 a compressed gas-air-mixture is contained between the partition wall 32 and the piston 4, as well as between the partition

wall 33 and the piston 3a; the mixture is ignited in known manner and the star consisting of the spokes 7, the connecting members 5 and 6, and the piston commences to 5 rotate in clockwise direction. Immediately prior thereto the combustion gases that were present in the space between the wall 33 and the piston 4a, as well as in the space between the wall 32 and the piston 3, had been driven 10 out through the apertures 13, and said spaces had then been scavenged by air fed by the blower 10 also in known manner; thereupon a fresh charge (gas-air-mixture) had been pumped into said spaces. At the stroke now 15 following the fresh mixture is compressed again in the usual manner and at the end of the stroke which again proceeds in clockwise direction this mixture is ignited and exploded, so that the piston star now runs in the op- 20 posite direction. This star moves, therefore uninterruptedly to and fro as long as always the same amount of the gas-air-mixture is supplied. This motion of the star is trans- 25 mitted by the free-wheel coupling 15, 16 as soon as the pistons circulate with the same number of revolutions as does the shaft 9. The engagement of the coupling members takes place free of shocks, and the rotatory motion is transmitted to the disk 19. As long 30 as the roll 17 is running upon the higher part of the cam disk 18, the friction roll 15 is held clamped fast between one arm of the lever 16 and the disk 19, and this disk is then taken round together with the star, but as 35 soon as the roll 17 gets into the deepened part of the cam disk 18, the friction roll 15 is released and the piston star runs without load, that is to say, is no more coupled with the motor shaft. The adjustment of the cam 40 disk 18 is effected by turning it about its axis 9 by means of the centrifugal governor 25. As this governor is coupled with and driven by the shaft 9, it runs with the same speed as the mentioned shaft. The quicker the 45 shaft 9 is running, the more the centrifugal regulator is raised and the disk 18 turned about its axis in clockwise direction and the longer will the roll 17, during one stroke of the piston star bear upon the cam disk 18, and the longer will the star remain coupled with the shaft.

The performance of the motor is determined chiefly by the stroke volume and the number of periods of the oscillating pistons. 50 This number is determined in turn chiefly by the mass of the pistons. If the performance of the motor is put down in a diagram according to Fig. 6, that performance would be proportional to the diagram surface from S to A, if S represents the point of time of the explosion, and A denotes the point of time at which the piston star is disengaged from the rotating shaft. Said diagram represents, of course, the output of only one 55 piston; the performances of the four pistons

cover and overlap one another more or less. The performance of the motor depends, thus, upon the number of revolutions of the shaft 9; with decreasing number, the turning moment which the motor produces increases 60 correspondingly, in that, with a small number of revolutions, the shaft 9 when being driven by the piston star turns through only a small angle, whereas the pistons continue their path without being coupled with the 65 shaft. Thus, with a small number of revolutions of the shaft 9 a larger number of working strokes of the piston star will exert their effect at one revolution of the shaft than with a larger number of revolutions. The 70 number of the working strokes acting at one revolution of the shaft 9 is determined by the adjustment of the cam disk 18, and this adjustment is regulated, in the example in question, by the number of revolutions of the 75 disk 19, so that when the motor runs more quickly and the turning moment to be performed is, therefore, smaller, a smaller turning moment is automatically provided for; that is to say, the motor is adjusted for a 80 smaller number of working strokes per one revolution, whereas, with a great resistance, thus, with slowly rotating shaft, the cam disk 18 is automatically so adjusted that a large 85 number of piston strokes takes place at one rotation of the shaft, in consequence whereof the turning moment is correspondingly increased.

It is, of course, also possible to adjust the cam disk 18 automatically, the centrifugal 90 governor being then dispensed with, but generally the automatic adjustment will be preferable.

The constructional form shown in Figs. 2 and 3 differs from that first described chiefly 105 by the feature that instead of the rotating shaft the cylinder itself rotates. Also in this case a circular or annular cylinder 34 is provided and is divided into two semi-circular spaces by walls 35 and 36. 37 and 38 are the pistons operating in said spaces; they are firmly connected with a disk 39 located within the annulus. The cylinder 34 is internally slotted and this slot is closed by the disk 39. The revolutions of the cylinder are 110 transmitted to the shaft 40 (Fig. 3). The disk 39 is connected with a crank 42 by means of a rod 41, and the crank pin 43 is supported in the cylinder body. The crank pin is connected with two cog-wheels 44 which 115 mesh with cog-wheels 45. One of these wheels runs freely upon a shaft 46, whereas the other runs freely upon a hollow shaft 47. The two cog-wheels 45 are firmly connected 120 by means of pins with cam disks 48 by means of which the valves 49 are controlled in the manner known with internal combustion machines. Thus, the four spaces p^1 , p^2 , p^3 , p^4 formed in the cylinder 34 are alternately supplied with the gas-air mixture; this is then 125

ignited and exploded and the pistons 37 and 38 are moved to and fro together with the disk 39. The shafts 40 and 46 are connected with each other by means of the torsion dynamometer 62-68. This coupling device is intended for automatically adapting the motor to the moment of the load, as fully described in German Patent No. 532,582, on page 3, lines 37-67.

For starting the motor a cog-wheel 50 may be provided which is connected in known manner with a pinion driven by an electro-motor or the like. This driving means have not been shown.

As long as the cylinder 34 being at a standstill, the pistons are reciprocated in the manner stated by ignitions taking place at the end of the strokes the energy they generate will be accumulated more and more, that is to say, they will move quicker and quicker until a certain maximum number of oscillations has been attained, without any outward transmission of the energy. For effecting this transmission, i. e. to the motor shaft, a ratchet-wheel clutch is provided in lieu of a friction clutch as in the first case. The disk 39 is either made integral with the hollow shaft 47, or these two members are rigidly connected with one another; it is supported in a bearing 51 which, together with the bearing 52 serving for supporting the shaft 40, constitutes a part of the frame 53.

The bearing 51 is provided with ratchet teeth 54 (Fig. 4) which can be engaged by a pawl 55 attached by means of a key 56a to a lever 56 provided with a pivot 57 for that purpose, and this lever is firmly secured to the hollow shaft 47. The solid shaft 46 arranged within said hollow shaft is firmly connected with the motor shaft 40, and at the free end of the shaft 46 is an abutment lever 58 which can engage a small projection 59 of the pawl 55. As long as this pawl engages the ratchet wheel 54 the hollow shaft 47 and, thus, also the disk 39 with the piston are prevented from turning relatively to the bearing 51, in consequence whereof the energy developed on the one hand between the pistons 37 and 38 and on the other hand between the walls 35 and 36 acts in such a direction that the cylinder commences to rotate. When the motion proceeds in the reverse direction the teeth of the ratchet wheel 54 can slide along the pawl and the pistons can, therefore, freely move back into their former position.

The pistons act, thus, when moving in the one direction as long upon the cylinder 34 and turn it as long as the clutch members between the ratchet wheel 54 and the pawl 55 are in engagement with one another, but this engagement is broken by the abutment member 58 which rotates together with the cylinder. According as the member 58 has been adjusted the disk 39 will be rendered sta-

tionary, together with the pistons 37 and 38, for a shorter or longer period of time, and owing thereto the energy developed in the motor will act upon the cylinder for a shorter or longer time. As, however, the number of the strokes remains the same, there will during that time in which the pistons are disengaged from the frame of the motor and can freely oscillate the developed energy be accumulated and the turning moment arising during, or at, the coupling procedure will be the stronger.

Reverting to the diagram shown in Fig. 6 I point to the feature that in the moment of the ignition a work corresponding to the surface from F to S is available. The hatched part of the diagram extending until A must at least be so large as to be able to do the resistance work for the compression in the cylinder, the expelling of the burned mixture, and the sucking in.

Referring to Fig. 2 it may be assumed that the pistons are moving in counter-clockwise direction. In this case a part of the performance in the space p^2 must be used for compressing the mixture in the cylinder p^3 , and then the burned mixture must be expelled and simultaneously therewith fresh mixture must be sucked into the cylinder p^4 . As soon as the piston 37 has approached the wall 36, another combustion takes place, so that the disk 39 now rotates in clockwise direction. This reversal of the movement would act retarding upon the cylinder 34, but requires, in fact, only a small fraction of its energy of motion as large masses are connected with the cylinder. That part of the energy which the cylinder has, indeed, given off is transmitted back to the piston 37 or 38 by the compressed gases, and this energy, as well as the entire work of the compressed gases, is transformed into vis viva of the pistons 37 and 38 and the masses connected therewith.

When then the next combustion takes place, in the space p^4 , viz. when the piston 38 has approached the wall 35, then the compressed gases turn the pistons and the mass connected with them again in counter-clockwise direction. The pawl 55 engages again the ratchet wheel 54 and the cylinder 34 is thereupon taken round, the energy accumulated in the piston being now transmitted to the cylinder.

The work of all four working strokes in the four spaces p^1-p^4 is transmitted to the cylinder 34 in the same direction, and a part of this mechanical work is transformed in continual alternation into vis viva of the masses oscillating together with the piston, and this vis viva is then re-transformed into mechanical work acting upon the cylinder 34.

The adjustment of the abutment member 58 may also in this case be effected by hand for the purpose of varying the turning

moment, but it is as well possible to make use of an automatically acting device. With the constructional form now described a torsion dynamometer is provided for that purpose, and in view thereof the cylinder 34 is not rigidly connected with the motor shaft 40, but a disk 60 is firmly affixed to this shaft and is coupled with the cylinder by springs 61 by the intermediary of drivers, and these springs are subjected to a greater or smaller tension and will be more or less expanded and this extension is utilized for the adjustment of the cam 58. For this purpose a cam 62 is connected with the shaft 40 (Fig. 5) and is provided with a pin 63 engaging a slot 64 of a lever 65; this slot is engaged also by a pin 66 projecting forth from the cylinder 34. The two pins determine the position of the lever 65. This lever is jointed by means of a pin 67 to a lever 68 firmly secured to the shaft 46. When the cam is turned in counter-clockwise direction relatively to the cylinder 34 and, thus, also relatively to the pivot 66, the lever 65 and, therefore, also the shaft 46 will be turned and this shaft turns, in turn, the abutment member 58.

The extent of the turning depends upon the shape of the slot 64 which can be designed as desired. By the adjustment of the member 58 the period of time during which the pistons are coupled with the frame is extended or shortened, and owing hereto the number of revolutions of the motor is decreased, simultaneously with an increase of the turning moment, or reversely.

In order to render the manner of operation of the device still more lucid, I state furthermore what follows:

The turning moment exerted upon the cylinder 34 is, apart from constructional data, dependent only upon the medium pressure which the compressed mixture exerts upon the walls 35 and 36 during one complete revolution of the cylinder. If the pawl is lifted very early then a large part of the working diagram (Fig. 6), say from F to G, is transformed into vis viva of the pistons 37 and 38. This energy is, when the direction of motion of the pistons has been reversed, first transformed into compression work and acts then in the opposite direction upon the pistons 37 and 38. This work or effect is assisted by the work of the combustion stroke in the space p^3 whereby the piston 37 is also accelerated. This piston receives, therefore, a considerable kinetic energy when its approaches the wall 35. In the given moment the ignition in the space p^2 takes place, whereby the cylinder 34 will be accelerated and the piston 37 will be retarded. In spite of the high pressure in the moment of the ignition the piston 37 is not momentarily stopped, but proceeds in its movement to the right counter to the gas pressure, and will

even approach the wall 35 and compress further the already ignited gases, which takes in the direction place to the line H in the diagram (Fig. 6). The thermic efficiency becomes correspondingly better. On that way which the piston 37 covers together with the wall 35, the piston transmits its kinetic energy completely to the cylinder 34. The medium pressure during one stroke can be ascertained from the surface between G and H, as well as from the path which the piston 37 and the wall 35 have jointly covered. The working strokes at a slow rotation and the high turning moments are for one revolution more numerous than with a quickly running motor and a low turning moment.

Theoretically the turning moment might be infinitely large if the cylinder 34 is held fast, as, since the pistons and the parts connected with them do not give off work exteriorly, another amount of kinetic energy is added at every working stroke. The pistons would thus move with higher and higher speeds, the stroke would become longer and longer, and the compression of the gases would continually rise. If the mass of the pistons 37 and 38 is spoken of, there is then meant, of course, the entire mass connected with said pistons, as well as the momentum of inertia of the same. As the motor changes its turning moment and its number of revolutions continually within large limits a separate change-speed gearing is not requisite. The motor can operate as a two-stroke cycle motor, as well as a four-stroke cycle motor, as desired.

Finally, another constructional form is shown in Fig. 7 in which actually aligned cylinders instead of the curved ones are employed; 70 and 71 denote these cylinders, and 72 and 73 are the pistons of the same; they are connected with one another by a rod 74. The waste gases escape through slots 75, and the scavenging air and the combustible charge is introduced through slots 76. Hinged to the rod 74 at 78 is a push rod 79 in which a pawl 81 is oscillable upon a pin 80. This pawl is designed as a double-lever and is provided at its free end with a roll 82 running along a cam 83 designed as a segment and supported loosely by means of a hub 84 upon the driven shaft 85. Firmly affixed to this shaft is a ratchet wheel 86 which said pawl can engage. Thus, when the pistons move to and fro, the movement is transmitted by the pawl 81 to the ratchet wheel and, thus, to the driven shaft 85. When the pawl is being moved by the intermediary of the guide rod 77, the roll 82 is being moved along the cam 83, and when it contacts with the thicker portion of this cam, it is lifted out of the ratchet-wheel and the piston is uncoupled from the driven shaft so that it can now continue to work in the already described manner and can accumulate energy. The adjustment of the

cam 83 is in this case effected manually by means of a grip 87.

I wish it to be understood that I do not limit myself to the constructional forms described and shown merely by way, of example, nor to all the details shown and described in connection with said constructional forms. Many departures are possible without departing from the characteristic features of the invention.

I claim:—

1. An internal combustion motor comprising, in combination, a cylinder, pistons movable within said cylinder, a shaft adapted to permit a free movement of the pistons in one stroke and to be coupled with the pistons in the counter stroke, clutch members coacting with said pistons during the counter-stroke thereby coupling them with said shaft, and means adapted to positively disengage the clutch members at any desired point of the counter-stroke.
